FOSTER J. SIBLEY, OF FINDLAY, OHIO, ASSIGNOR OF ONE-HALF TO THOS. C. DUNN, OF FINDLAY, OHIO.

COMPUTING COUNTER-SCALE AND CASH-REGISTER.

1,112,388.

Specification of Letters Patent. Patented Sept. 29, 1914.

Application filed September 7, 1905. Serial No. 277,318.

To all whom it may concern:

Be it known that I, FOSTER J. SIBLEY, citizen of the United States, residing at Findlay, in the county of Hancock and State of Ohio, have invented certain new and useful Improvements in Computing Counter-Scales and Cash-Registers, of which the following is a specification.

My invention relates to computing scales, and it also relates to recording devices for recording the values determined by the scale, and it relates also in its nature to cash registers.

The object of the invention is to produce an improved computing scale in which the value of the article weighed will be indicated upon a single tablet in plain figures.

A further object of the invention is to provide means by which the amount thus indicated will be permanently recorded.

A further object of the invention is to so combine the recording and indicating devices with certain keys that it may be used as a register to register cash, the construction being such that the device may be used as an ordinary scale, as a computing scale, as a recording computing scale, as a cash register for determining the amount in value of the article weighed and a comparison of the cash receipts therewith, or as a cash register separate and apart from the scale.

With these general objects and other subsidiary objects that will appear from the specification, the invention consists in the construction and combinations hereinafter described and set forth in the claims.

In the accompanying drawings, Figure 1 is a perspective view on the line 2—2 of Fig. 4 of a device embodying my invention. Fig. 2 is a longitudinal sectional view of the recording or registering operation of the same on the line 3—3 of Fig. 2. Fig. 3 is a transverse sectional elevation of the same. Fig. 4 is a transverse elevation of the same taken on a different plane on the line 4—4 in Fig. 2. Fig. 5 is a detail view of the indicating tablets. Figs. 6 to 13 inclusive are detail views of some of the various parts which will be referred to hereinafter. Fig. 14 is a view of the ratchet wheel and the retaining pawl therefor. Figs. 15 and 16 are detail views of the spring actuated retaining pawl. Fig. 17 is a detail view of the means for covering the weight indications and lock therefor. Fig. 18 is a detail view of the engaging

locks between the measuring wheel and the first indicating wheel. Fig. 19 is a detail view of several of the operating keys of the series. Fig. 20 is a detail view in perspective of an indicating tablet with the record-making type thereon. Fig. 21 is a view of a portion of the mechanism in modification.

Like parts are indicated by similar letters of reference in the several views.

The general object of my invention is to employ a scale which is generally known as the automatic type, that is, one in which articles of different weights produce a greater or less movement of the parts which are counter-balanced by a weight, pendulum or spring, as the case may be, the construction being such that the heavier the weight the greater the range of movement of the parts.

With this scale I provide a measuring device in the form of a wheel which is adapted to measure the extent of movement of the scale proper. This measuring device is preferably provided with graduations showing pounds and ounces, from which the true weight of the article can be ascertained. In connection with this measuring device, I employ a series of indicator frames, each frame representing a certain price per pound, and each containing a series of indicators representing computations of the given price per pound to which it corresponds multiplied by the weights of the various articles.

Means are provided for bringing any one of these series of indicators into proper relation with the measuring device, so that the proper indicator of this series will be brought into the position determined by the measuring device to indicate the value of the article weighed at the price per pound corresponding to the indicator, means being also provided for exposing this indicator after the same has been brought to the proper position. In connection with these indicators, a series of printers are employed as a part of a recording or accounting device, so that the amount exposed by the indicator is recorded on the recording or accounting device, and a permanent record made of the value of the article weighed.

In connection with these indicators, and preferably in the casing which contains the same, I employ a cash drawer into which the cash received for the article weighed is placed so that the device becomes a cash

register by recording the cash received for the different articles at their true value, as indicated by the tablets. A series of keys are used, one for each series of indicators, 5 and these keys represent the different prices per pound of the articles to be weighed, and these keys are used in exposing the indicators after they have been brought into proper position determined by the measuring device. These keys are also so arranged 10 that they may represent amounts of cash, independent of the values of the articles weighed, so that the device may be used, to this extent, as a cash register pure and simple.

For convenience in illustrating my invention, I have shown a simple form of scale of the pendulum type, which is mounted on a base or frame, *a a*. A standard, *a¹*, on 20 this base carries the main lever, *b*, which is pivoted by the proper knife-edged bearings from the standard, *a¹*, and is attached at its outer end, as shown at *b¹*, to a strap, *b²*, which passes over a suitable cam, *b³* 25 on the upper end of the pendulum, *c*. The scale platform is shown at *d*, and it is connected to the main beam, or lever, *b*, through a suitable beam connection, *d¹*, and link, *d²*, the platform being provided with the 30 usual vertical stem, *d³*, and check-rod, *d⁴*. The beam, *b*, is also preferably provided, in the usual way, with a tare-beam, *b⁴*, by means of which the tare may be determined 35 by counter-balancing a receptacle upon the platform, by the poise *b⁵*, on the tare-beam, or by weighing in pounds and ounces on the tare beam the articles placed on the platform which is to be deducted as tare.

Adjacent to the main beam, *b*, and preferably mounted upon the same base, *a a*, is a casing, *e e*, which contains the computing mechanism, the indicators and recorders, the bottom of the casing being provided with a space for a cash drawer, 45 *e¹*, as shown.

The pendulum, *c*, carries at its upper end means for transmitting motion to a measuring device, this means being in the device shown a gear segment, *f*, which meshes with 50 a pinion, *f¹*, on the end of the shaft, *f²*, which projects through the casing, *e*. This shaft has, on its other end, a wheel *g*, which I have termed the measuring device or measuring wheel. It is preferably provided upon its periphery with a series of 55 graduations and numerals representing pounds and ounces, the construction being such that any movement of the main beam will be transmitted through the gear segment 60 and the pinion to the measuring wheel, *g*. This measuring wheel, *g*, lies just within the casing, *e*, and its periphery is adapted to be exposed through an opening, *g³*, in the casing, through which the weight indicated on the measuring wheel may be

seen. This opening, *g*, is preferably provided with a cover by which the opening may be closed so that the weight cannot be exposed, for a purpose hereinafter specified. The inner end of the shaft *f²* is preferably supported in a standard, *h*, within the casing. This standard also supports one end of the main shaft *i* which extends entirely through the casing, and which is preferably in line with the shaft, *f²*, but entirely separated therefrom. The other end of the shaft, *i*, may be supported in a suitable bearing, *i¹*, at the end of the casing, *e e*. On this main shaft, *i*, are a series of wheels or rotating frames *j*, each 80 one being secured to the shaft, *i*, and turning therewith. These wheels or frames are provided near their outer periphery with projecting flanges, *j¹* and *j²*, in which are mounted indicators *j³* (see Fig. 5 for detail). Each of these indicators is mounted on a short stem, and is normally held in its unexposed position between the flanges, *j¹ j²*, by a stem *j⁴*. The indicators and their stems are placed on radial lines extending 90 from the outer periphery of the wheel or frame toward the center of the shaft, *i*. All these indicating frames or wheels are alike, the indicators or tablets, however, in each wheel being different. Means are 95 provided for rotating the shaft, *i*, and with it these different indicator wheels or frames carrying the indicators. For this purpose, I have shown a hand-lever, *k*, which projects through the outer casing and is journaled at its inner end on a shaft *k¹* supported on an arm, *h¹*, of the standard, *h*, which supports the end of the main shaft, *i*. This shaft, *k¹*, carries a pinion, *k²*, which meshes with the pinion, *i²*, on the shaft *i*. 100 A spring pawl, *k³*, is adapted to engage the teeth of the pinion, *k²*, and thus, as the hand lever, *k*, is moved, to rotate the shaft *i*. The measuring wheel, *g*, is provided on one side with a projecting lug, *g¹*, and the first indicating wheel or frame, *j*, is preferably provided with an oppositely extending and over-lapping lug, *j³*, which is adapted as the indicating wheels are turned, to contact with this lug or stop, 115 *g¹*. Means are provided for locking the measuring device in any position to which it may be turned by the operation of the scale, and the indicator wheels, or frames, are brought to the same relative position 120 by revolving the shaft, *i*, until the lug, *j³*, contacts with the lug, *g¹*, on the measuring wheel. This brings all the indicators in their proper position to indicate the value represented by the weight of the article measured on the measuring wheel, the different indicator wheels representing the different prices per pound. There is within the indicator wheel a device adapted to contact with any indicator stem of that 125 130

wheel which may be brought opposite thereto, and by operating this device the proper indicator representing the value may be pressed outward and thus expose the 5 exact value of the article weighed. For this purpose I employ keys, l , which are preferably arranged just above the drawer, e^1 , near the bottom of the casing. Each of these keys is mounted on one end of a 10 lever, l^1 , the opposite end of which carries a rod, l^2 , which extends upwardly and along the side of the indicator wheel, and is there bent inwardly and upwardly as shown at l^3 , so as to project immediately 15 under the indicator stem and opposite thereto. The indicator stem is preferably provided with a cup-shaped bearing at the bottom of the projecting ends, and the rod l^2 is preferably slightly conical to fit into 20 said cup-shaped bearing, so that a proper contact will be made between the two, to insure the indicator being raised when the key is depressed.

In addition to the indicator, there is provided 25 a printing device, one for each indicator and having the same figures thereon. These are preferably formed as shown at j^6 in Figs. 4 and 5. At the upper end of the indicator proper, and immediately above the 30 indicating wheels at a distance therefrom equal to the movement of the indicators is a platen against which the printing devices are adapted to be brought as the indicators are elevated by the proper key. This platen is preferably in form of a wheel, m , partly 35 around which extends a tape, m^1 . This tape may be moved in any well known manner, around the wheels, from a reel, m^2 , and onto a receiving wheel, m^3 . Means are provided 40 for giving the tape a given movement after each indication. Any suitable inking devices may be employed to ink the type, or an inking ribbon may be used in the usual way as shown at m^4 in Fig. 2, or 45 the type may be of such a character as will make an impression without the use of ink. It will be seen that as the indicators are forced upwardly not only will the amount of the indicator be exposed, but a permanent 50 record will be made thereof on the record strip, m^1 .

As before mentioned, any well known or suitable means may be employed to advance the record strip m^1 after each operation. 55 However, the mechanism illustrated in the drawing for this purpose consists of a pair of intermittently operating feed rolls, o o' , provided with intermeshing gears as shown in Figs. 2 and 3. The feed roll, o , is further provided with a ratchet, o^2 , engaged by a pawl, o^3 , on a vertically moving rod, o^4 , which in turn is connected to an operating lever, o^5 , pivoted at o^6 to the frame of the machine. A projecting roller, o^7 , on the lever, o^5 , engages an inclined groove or slot,

o^8 , in the side of the drawer, e^1 . Upon the opening and closing of the drawer, the lever o^5 is positively moved to cause a reciprocating movement of the rod, o^4 , which transmits movement to the feed rolls, o o' through the pawl, o^3 , and the ratchet wheel, o^2 , thus advancing the record strip, m^1 , a predetermined distance preparatory to the next operation.

Means are provided for locking the measuring wheel in the proper position determined by the article on the scale platform before the indicators are moved to the position governed by said measuring wheel. For accomplishing this, I have shown a 75 cam, i^6 , on the main shaft, i , which is adapted, at the first movement of said shaft, to operate a spring-actuated rod, n , which is attached at its lower end to a pivoted lever, n^1 , which carries at its outer end a pawl n^2 , to engage the notches, g^2 , on the periphery of the measuring wheel. The shaft, i , also carries at its opposite end a ratchet wheel, i^4 , and is preferably provided with numbers corresponding to those on the measuring 80 wheel, except that they are run in the reverse direction, and are exposed to an opening in the back of the casing to permit the customer to read the weight of the article weighed after the indicators have been set. 85

For the wheel, i^4 , there is provided the same arrangement of cam, i^6 , rod, n , lever, n^1 and pawl, n^2 , as for the measuring wheel, g , the only difference being that the part, n^2 , instead of being a pawl adapted to contact directly with the wheel is more of a pawl holding arm. A small spring pawl, n^3 , (Figs. 15 and 16) is located in the top of this part n^2 , to engage the ratchet teeth of the wheel, i^4 , to permit said wheel to turn in one direction and hold it against revolution in the opposite direction. (See Fig. 14 for detail). Each of these holding pawls are adapted to be thrown out of contact with their respective wheels by the operation of the drawer, means for accomplishing this being shown in detail in Figs. 11 to 13. The pawl arms n^2 are made in two parts and hinged together as shown at n^4 , the lower part, n^5 , being adapted to contact 100 with a cam formed in the edge of the cams n^6 n^7 on the drawer. These cams are so arranged that as the drawer opens, the hinged end, n^5 , of the pawl will be deflected until it has passed the cam projections, when 105 it will be returned to its normal position by the spring, n^8 . As the drawer is closed, the cam will be engaged on the opposite side of the hinged portion, n^5 , and the whole pawl will be deflected in the opposite direction, 110 as shown in Fig. 12, and thus release the respective wheels. When released, the measuring wheel will return to its normal position as soon as the article has been removed from the weighing platform. For 115

returning the indicator wheel and main shaft to normal position, the ratchet wheel, i^4 , is provided with a coil spring, i^5 , as shown in Fig. 14, which returns all the parts to zero.

In order to expose the indicator for a definite period of time, means are provided for holding the keys, l , depressed. This may be accomplished by spring actuated catches, 10 l^2 , secured on a shaft, l^5 , extending across the machine and having a downwardly projection arm, l^6 , adapted to contact with a movable stop, l^7 , on the drawer. As any key is depressed its catch, l^2 , is adapted to 15 catch on a pin or projection, l^8 , in the key and hold the same depressed. The movable stop, l^7 , is pivoted to the drawer in such a manner that as the drawer moves outwardly it will pass the projection, l^8 , but 20 as the drawer is moved inwardly it will contact with said projection and thus oscillate the shaft and withdraw the catches from the keys, allowing the keys as well as the elevated indicator to return to normal 25 position. A rod, p , extending across the machine under the keys, and supported in suitable pivoted arms at opposite ends one of which carries a locking pawl, p^1 , is arranged under the keys so that when any 30 key is depressed the pawl will be elevated and thus unlock the drawer; a spring being employed to force the drawer outwardly when unlocked in the usual well known manner. The cam projection for unlocking 35 the wheels and the movable stop for unlocking the keys are so timed that the keys will be unlocked first and the indicator proper be returned to normal position before the wheels are unlocked, these functions being preferably performed as the 40 drawer is closed. It is obvious, however, that any other timing device may be used if desired.

A brief description of the operation of the 45 device is thus described and the order of its sequence is as follows:—The article placed on the scale moves the measuring wheel a distance corresponding with its weight, the weight being indicated by the 50 graduations on the periphery of the wheel. The shaft, i , is then turned by the lever, k , the first movement of the shaft through the cams, i^6 , throws the locking pawls into engagement with the measuring wheel and 55 the ratchet wheel respectively. The measuring wheel will be held permanently locked, the ratchet wheel will be permitted to turn in one direction but locked against revolution in the other direction. The shaft 60 is turned and with it all the indicating wheels, until the overlapping projections on the indicator wheel and measuring wheel respectively contact, thus forming a stop against further revolution of the indicating 65 wheels. The lever, k , may require several

movements to bring the indicator wheels to proper position and when released will be returned to its normal position by the spring, k^4 , the indicating wheels and the main shaft by which they are carried being 70 locked in their moved position by the pawl, n^3 , engaging the ratchet wheel, i^4 , thus exposing the weight of the article to the customer through the back of the casing by means of the graduations on the periphery 75 of the wheel, i^4 . The key representing the price per pound of the article is now depressed and will carry upwardly the indicator which has been brought into position immediately opposite the rod or carrier 80 attached to the key, and this particular tablet will indicate the value of the article as determined by the particular price per pound represented by that key. As the key is depressed it will also bring the printing 85 device in contact with the record strip and print the amount representing the value of the article upon this strip. The key will be locked in this position and the amount exposed so long as the drawer remains open, 90 it being understood that the drawer will also be opened by the depression of the key.

For use as a cash register, the first, or what might be termed the zero tablet, being the one which would be opposite the tablet 95 carrier when the wheels are in their normal position, instead of being marked "Zero" may be marked the same value as the key, so that in case the key is depressed without moving the indicator wheels an indicator 100 corresponding to the key will be raised, and thus permit the device to be used as a simple cash register, this part of the operation being independent of the weighing.

As is well known, by adding a weight 105 to the pendulum as shown for instance in Letters-Patent No. 674,646 to Allen De Vilbiss, Jr., May 21st, 1901, the capacity of the scale may be doubled; that is to say, the price per pound would be given a different value. This feature is old in pendulum scales and is usually employed with a weight which gives just double the values, that is to say, a price per pound which ordinarily would be 5¢ would, with the 110 weight attached to the pendulum, become 10¢, and these have generally been used in connection with a double set of figures printed in different colors, one color being used with the weight and the other color without 115 the weight. This method of increasing the capacity of the scale may be employed in my improved device. Each key may be provided with a double set of numbers printed in different colors, one set of figures being employed with the weight and the other without. My device, however, has the distinctive advantage in this case that the same tablets will be employed whether with or without the weight and a single indication will 120 125 130

always be given so that all danger of confusion, such as arises on chart scales or those scales which employ value figures as well as price figures in different colors, will be avoided. When the weight is used the measuring wheel will be moved only one-half as far. In this case, the lower values will be used with the weight and the higher values without the weight, that is, an article weighing 5 lbs. would move the measuring wheel one-half as far with the weight on as it would with the weight off. At 5¢ a lb., for instance, the 5¢ indicating wheel would be moved to expose the 25¢ tablet 70 when the weight is employed and to expose the 50¢ tablet when the weight is not employed. If desired, the keys may be employed with a different set of figures than the price per pound figures to be used as a 75 register. In this case, there will be three figures on each key, instead of two, as indicated in Fig. 19, these additional figures being used only for registering cash transactions independent of the weighing, the 80 25 normal or zero tablets in each of the indicating wheels being numbered corresponding to these other figures. These figures could be run in multiples of 5 or 10 to give a larger capacity for registering cash independent of the scales. Thus with fifteen 85 keys, the first key being numbered 5 and the others in multiples of 10 to 90 and then in multiples of \$1.00 to \$5.00 a machine capable of registering multiples of 5 up to \$5.95 would be secured and this independent of the figures representing the price per pound value, of which there might be thirty, assuming the detachable weight to be employed in connection with the pendulum. 90 40 I preferably employ means for covering the weight indications when it is desired. This may be done by providing a cover and a lock so that the weight indications will not be exposed as shown in Fig. 17. In 45 this case a clerk operating the device would necessarily be governed wholly by the tablet and would be required to collect the exact amount indicated by the tablet, and could not use the scale at all unless an indication 50 and a permanent record was made. Where the graduations are exposed on the measuring wheel, it would be possible, of course, to weigh an article in pounds without using the computing part as the exact weight 55 55 would be exposed from the measuring wheel. It will be seen that a device of this kind not only gives an accurate calculation and shows by a single indication the exact value of the article weighed, but it makes a permanent record and it produces a machine by which simple weighing may be done or computing weighing may be done and a registration obtained of the articles weighed in value or of cash collected, both for articles weighed or independent of the weighing.

It may be desirable to have an additional key (see Fig. 19) adapted to print on the record strip a sign or character indicating when the device is used as a cash register pure and simple, then all those items which represent cash registered independent of the weighing could be readily determined on the detail strip. 70

As shown in Figs. 2 and 18 the indications would not be permitted a complete revolution as the projections, g^1 , and, i^3 , could not pass the post, h . The revolution permitted, however, would be sufficient for ordinary purposes as it could be complete with the exception of the thickness of the post. 75 I have shown, however, in Fig. 21 a modification which would permit a complete revolution of all of these parts. In this view I have shown the shaft, i , extended so as to overhang slightly the bearing, h^1 , and on this extended portion I have mounted a wheel or disk, i^2 , and mount the projection, i^3 , on this disk instead of on the indicating wheel, j . 80 85

Having thus described my invention I claim:—

1. The combination of computing scales, a rotating circular frame, a series of normally concealed indicators in said frame, each of said indicators containing a single 90 value indication, a price key, means independent of said key for rotating said frame, a weighing scale, devices operated by said scale for controlling the movement of said frame, and a device connected with said key 100 which will permit a complete revolution of said frame but adapted by the movement of said key to expose any one of said indicators as determined by the movement of said frame, substantially as specified. 105

2. The combination, with a weighing device, of a series of keys representing prices-per-pound, a series of indicator frames, each frame having a plurality of normally concealed indicators representing different 110 values, means for moving said frames, means operated by the weighing device for controlling the movement of said frames proportionate to the weighing movement of said weighing device, and separate means for exposing any one of said indicators by a movement of its corresponding key, substantially 115 as specified.

3. In combination with a scale, a measuring wheel moved by said scale, an indicator frame having a series of normally-unexposed value indicators, means for moving said frame, means on said measuring wheel for determining the movement of said frame, a price key having means for exposing any 120 one of said indicators on said frame, and printers to record the values indicated by said indicators, substantially as specified.

4. The combination with a scale, a measuring wheel moved by said scale, a series of 125

- keys representing prices-per-pound, a series of indicating wheels each having a series of normally concealed indicators representing values, means for moving said wheels, means on said measuring wheel for determining the movement of said wheels, and means connected with each of said keys adapted when a key is operated to expose an indicator representing a value determined by the depressed key and the position of the indicating wheel corresponding thereto, substantially as specified.
5. The combination with a scale movable to different positions in proportion to the weight of the article weighed, accounting mechanism having a series of movable members for recording different values in proportion to the movement of said scale, means for moving said members, an intermediate 70 measuring device moving with said scale to control the movement of said members, and means representing prices for operating said members after they have been moved to a given position.
10. The combination of a scale, a series of indicating devices, a series of indicators carried by each indicating device movable relatively thereto and each having a value indication, means for moving said indicating device, means on said measuring device for controlling the movement of said indicating device, a key representing the price, and means connected with said key for operating 75 any one of said indicators to indicating position dependent upon the movement of said measuring device.
15. The combination of a scale, a series of indicating devices, a series of indicators carried by each indicating device movable relatively thereto, an intermediate measuring device, a connection between said measuring device and said scale to cause said measuring device to move therewith, means for moving all of said indicating devices, means connected with said measuring device for determining the movement of said indicating devices, a series of keys, and means connected with each key for operating a single indicator to indicating position in one of the indicating devices determined by the position of said indicating device, means for locking said measuring device, and a printer connected with each indicator to print an amount equal to said indicator.
20. In an indicating device for computing scales, the combination, with a scale, of a rotary circular frame having a series of normally-unexposed indicators extending around and within its periphery, each indicator representing a single value indication, means for rotating said circular frame to different positions, means operated by the movement of said scale for controlling the movement of said frame, and a single operating means adapted to permit a complete revolution of said circular frame and, when operated, to expose any indicator therein dependent upon the movement of said circular frame.
25. The combination, with a scale, of a measuring device adapted to move with said scale, means for locking said measuring device, value indicators adapted to be moved independent of said measuring device but controlled thereby, means for normally concealing said indicators and means for exposing a single value indicator at a given price to represent a value determined by the movement of the scale.
30. The combination of a scale, an intermediate measuring device moved by said scale proportionately to the weight on said scale, an indicating device including a series of indicators, means for moving said indicating device and locking said measuring device, means connected with said intermediate measuring device for controlling the movement of said indicating device to select one of said series of indicators corresponding with the weight on the scale, and independent means for moving the said selected indicator.
35. The combination, with a scale, of a measuring device graduated in weight graduations, a connection between said scale and measuring device to cause said measuring device to move with said scale, an indicating device, a series of indicators carried by said indicating device movable relatively thereto and each having a value indication, means for moving said indicating device, means on said measuring device for controlling the movement of said indicating device, a key representing the price, and means connected with said key for operating 70 any one of said indicators to indicating position dependent upon the movement of said measuring device.
40. The combination of a scale, a series of indicating devices, a series of indicators carried by each indicating device movable relatively thereto, an intermediate measuring device, a connection between said measuring device and said scale to cause said measuring device to move therewith, means for moving all of said indicating devices, means connected with said measuring device for determining the movement of said indicating devices, a series of keys, and means connected with each key for operating a single indicator to indicating position in one of the indicating devices determined by the position of said indicating device, means for locking said measuring device, and a printer connected with each indicator to print an amount equal to said indicator.
45. The combination, in a computing or price scale, of recording and indicating devices for recording and indicating values, means for placing said recording and indicating devices in indicating and recording position together with means controlled by the scale for determining this position, and keys having means for operating said recording and indicating devices to recording 100 and indicating position independent of the operation of the scale.
50. In a computing scale, a series of normally unexposed indicators, means for normally concealing said indicators, means for selecting the position of said indicators controlled by the weighing movement of said scale, and a price key and connections adapted when operated to expose the indicator representing the value determined by the weight and price on the scale and key, respectively.
55. In a computing scale, a plurality of indicating devices each having a series of normally-concealed individual indicators representing values, means for moving said indicating devices, means for controlling the movement of same by the weighing movement of said scale, a series of price keys, one for each indicating device, and means upon 105 the operation of any one of said keys for operating a single indicator of the indicating device corresponding to said key and thus expose a single value at a given price.
60. In a computing scale, the combination 110
65. In a computing scale, the combination 115
70. In a computing scale, the combination 120
75. In a computing scale, the combination 125
80. In a computing scale, the combination 130

- of a recording mechanism and an indicating mechanism adapted to record and indicate values, means for setting same in recording and indicating position, means operated by 5 the scale for controlling the setting of said mechanisms, and a price key having means for operating said recording and indicating mechanisms to record and indicate the value of the article weighed by said scale.
- 10 15. The combination of a computing scale, a plurality of series of normally concealed indicating and recording devices to indicate and record single values at different prices, means for setting said indicating and 15 recording devices, means controlled by the
- weighing movement of said scale for determining the setting of said indicating and recording devices, and a series of price indicating devices adapted to operate said indicating and recording devices to expose and 20 record the value determined by the price and weight of the article weighed, substantially as specified.

In testimony whereof, I have hereunto set my hand this 15 day of July A. D. 1905.

FOSTER J. SIBLEY.

Witnesses:

MARION G. FOSTER,
THOS. C. DUNN.
